SPOON OR SIMILAR ARTICLE

Ellen B. Manderfield, Syracuse, N.Y., assignor to
Oneida Ltd., Oneida, N.Y.

Filed Sept. 28, 1973, Ser. No. 401,709

Term of patent 14 years

Int. Cl. D7—03

U.S. Cl. D7—137

FIG. 1 is a front view of a spoon showing my new design;

FIG. 2 is a side view thereof on a reduced scale; the undisclosed side being substantially identical with the side shown in FIG. 2;

FIG. 3 is a rear view thereof on a reduced scale;

FIG. 4 is a cross-section taken on line 4—4 of FIG. 1; and

FIG. 5 is a cross-section taken on line 5—5 of FIG. 1. I claim:

The ornamental design for a spoon or similar article, substantially as shown and described.
